BRASSIÈRE

Jacques Heim and Marie Rose Lebigot,
Paris, France

Application April 5, 1949, Serial No. 1,815
In France January 27, 1949

Term of patent 14 years

(Cl. D20—4)

To all whom it may concern:

We, Jacques Heim and Marie Rose Lebigot, citizens of France and residing in Paris, France, have invented a new, original, and ornamental Design for a Brassière, of which the following is a specification, reference being had to the accompanying drawing, forming a part thereof, in which the figure on the drawing is a front perspective view of a brassière showing our new design.

We claim:

The ornamental design for a brassière, substantially as shown.

JACQUES HEIM.
MARIE ROSE LEBIGOT.
